(57) **CLAIM**

The ornamental design for a physiotherapy sleeping bag, as
shown and described.

DESCRIPTION

FIG. 1 is a front perspective view of a physiotherapy
sleeping bag, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is its state diagram; and,

FIG. 9 is an enlarged detail view of area 9 in FIG. 1.

The broken lines in the drawings illustrate the portions of the
physiotherapy sleeping bag, which form no part of the
claimed design.

The dash-dot-dash broken lines encircling the enlarged
views are for annotative purposes only and form no part of
the claim thereof.
